Specification of Letters Patent.

Patented Nov. 10, 1914.

Application filed March 14, 1913. Serial No. 754,832.

To all whom it may concern:

Be it known that I, THOMAS S. APGAR, a citizen of the United States, and a resident of Robinson, in the county of Crawford and State of Illinois, have invented a new and useful Improvement in Underreamers, of which the following is a specification.

My invention is an improvement in under-reamers, and has for its object to provide a tool of the character specified, especially adapted for under-reaming well casings, as for instance, in gas, oil or other wells, wherein the reaming mechanism may be contracted within a diameter less than that of the interior of the well casing to permit the passage of the tool through the casing, and wherein means is provided for automatically expanding the reaming mechanism when the proper position is reached, and wherein the parts may be again contracted to permit the removal of the tool from the casing.

In the drawings:—Figure 1 is a longitudinal section of the improved under-reamer, with the bits in contracted position, Fig. 2 is a longitudinal section at right angles to Fig. 1, Fig. 3 is a section on the same plane as Fig. 1, with the bits expanded, Fig. 4 is a section on the same plane as Fig. 2, with the bits expanded, Fig. 5 is a perspective view of the under-reamer, Fig. 6 is a perspective view of the internal parts in separated position, Fig. 7 is a perspective view of the expanding wedges and their supports, Fig. 8 is a perspective view of the bits and their support, Figs. 9, 10 and 11 are sections on the lines 9—9, 10—10 and 11—11 respectively of Fig. 1, and Figs. 12 and 13 are sections on the lines 12—12 and 13—13 respectively of Fig. 3.

40 The present embodiment of the invention comprises a tubular casing 1, having oppositely arranged longitudinally extending slots 2, intermediate its ends, and a head is connected with the upper end of the casing. 45 The said head comprises a body 3, rectangular in cross section, having at its ends integral disk flanges 4 and 5 respectively.

The head is provided at the flange 4 with a threaded stem 6, and at the flange 5 with a cylindrical lug 7, which is received within the upper end of the casing 1, and is secured thereto by means of the cross pin 8. The stem 6 is adapted to engage the hoisting and lowering mechanism for the tool, and the

rectangular body 3 is adapted to be engaged by a wrench or the like, to attach the tool to the said hoisting and lowering mechanism. The flange 5 of the head fits against and closes the upper end of the casing.

A tubular dog support 9 is arranged within the casing, adjacent to the head, the said support having a transverse opening 10, near its upper end, which is engaged by a pin 11, passing through the support and the casing, to hold the said support in position. The support is provided with longitudinally extending oppositely arranged similar arms 12, at its lower end, and the space between the arm at each side of the said support is approximately key-hole shape, to receive the keys shown in Fig. 6, each of said keys comprising a head 13, and a stem 14. The said keys fit within the said spaces, and the operating dogs 15 fit against the keys. Each of the said dogs is provided at each end on its inner side edge with a cross head 16, and the arms 12 of the dog support are notched as indicated at 17, to receive the said cross heads to prevent vertical movement of the dogs when they are so engaged. It will be noticed that the lower end of each of the keys 13—14 is beveled on its inner face as shown at 18.

The bit support 19, shown in detail in Fig. 8, is provided at opposite sides with longitudinally extending grooves 20 for receiving the bits 31. Each of the said bits is reduced at its upper end to form a neck 22, and the groove 20 of the bit support is similarly reduced to engage the sides of the neck closely. At the upper end of the neck each bit is provided with oppositely extending lugs 23, and the bit support has recesses 24 at the upper ends of the grooves for receiving the said lugs 23.

When the parts are in the position shown in Fig. 8, the bits may be engaged with the support 19, by introducing them from the lower end of the support. The groove 20 is of sufficient width to permit the passage of the lugs 23, and the reduced portion of the groove 20 has a passage 25, connecting the lower end of the groove with the adjacent recess 24. The grooves 20 are of greater depth than the thickness of the bits, and the passage 25 is at the bottom of the grooves, so that after the lugs 23 have passed through the passages 25 and into register with the

recess 24, an outward movement of the bit will engage the lugs 23 with the said recesses to prevent downward movement of the bits with respect to the support. At 5 opposite sides of the bit, shoulders are formed between the main portion and the neck, and each of the said shoulders consists of two oppositely beveled portions 26 and 26^a respectively. At the lower end of the 10 reduced portion of the grooves 20 beveled shoulders 27 are formed, for engagement by the shoulders 26—26^a. The arrangement of the said shoulders 26—26^a permits some rocking movement of the bit on the shoulders 27. The support is also provided with an upwardly extending lug 28. It will be noted that when the bits are in place on the support and in inward position the rounded outer surface of the bits is uniform with the 15 rounded outer surface of the support to form a substantially cylindrical body.

The spreading wedges 29 are arranged between the bits and the support, each wedge having an upwardly extending stem 30, provided at its upper end with a transverse opening 31. Each of the wedges 29 has an extension 32 connecting the said wedge with its stem, and the outer face of each extension is rabbeted at each side edge as indicated at 33. The width of the rabbet is approximately the width of the passage 25, so that the rabbeted edge of each wedge extension moves within the said passage, while the lower end of the rabbet forms a stop for 35 limiting the upward movement of the wedge. Each wedge is also provided with a transverse opening 34, at its lower end for a purpose, to be presently described. A wedge support 35 is provided, the said support having 40 oppositely arranged notches or recesses 36 at its lower end for receiving the upper ends of the stems 30, and the support is provided with an opening 37 at the said recesses for registering with the openings 31 of the 45 stems, and a headed pin 38 is passed through the registering openings 31—37 to connect the stems to the wedge support. The upper end of the wedge support is also recessed on opposite faces, as indicated at 39, and the 50 said recesses are between the recesses 36, or at right angles to the said recesses.

The support is provided with an upward extension 40 at its upper end and the upper end of the extension is reduced as indicated 55 at 41, the extremity of the reduced portion being rounded as indicated at 42. The reduced portion 41 (when the parts are in the position of Figs. 1 and 2) is received between the keys 13—14, as indicated in the 60 said Figs. 1 and 2, and the lower beveled ends 18 of the said keys fit against the beveled shoulders 43 at the junction of the reduced portion with the main portion.

A coil spring 44 encircles the stems 30 between the upper end of the lug 28 of the bit

support and the lower end of the wedge support. The dogs 15 are arranged within the slots 2 of the tubular casing and the said dogs move in the said slots, the slots being of approximately double the length of the 70 dogs.

In the use of the tool, when it is desired to introduce the same into the well casing 45, the wedges are drawn down until they extend below the lower end of the bit support 75 as indicated in Figs. 1 and 2. The bits swing inward as shown in the said figures until their outer surface is flush with the outer surface of the tubular casing. The dogs 15 are at the upper ends of the slots 2, 80 the cross heads 16 thereof being received within the notches 17 of the dog support 9. The reduced portion 41 of the wedge support is received between the stems 14 of the keys 13—14, and the coil spring 44 is compressed. 85

The wedge support 35 cannot move upward because of the engagement of the end 42 thereof with the heads 13 of the keys and because of the engagement of the shoulders 43 thereof with the beveled ends 18 of the stems of the keys. The heads 13 of the keys have their inner surfaces in contact, thus closing the opening 46 at the lower end of the tubular portion of the dog support 95 and as long as the dogs 15 are in this position, the keys are so held to prevent upward movement of the wedge support. After the tool has passed below the lower end of the well casing 45, the spring 44 will expand and 100 will move the wedges and the wedge support upward. The shoulders 43 of the said support will spread the lower ends of the keys 13—14 apart, pushing out the lower ends of the dogs and pushing out the cross head 16 at 105 the said lower end from the adjacent recess 17.

The end 42 of the support will spread the heads of the keys and push out the upper ends of the dogs, disengaging the cross 110 heads at the said ends from the upper notches 17, and the reduced end 41 will pass through the opening 46 into the interior of the dog support. The dogs 15 now occupy the position of Fig. 3, and the bits 21 are 115 expanded. It will be noticed that each bit is beveled at its lower end from within outward to form a cutting edge at the outer corner of the lower end, and when the tool is operated in the usual manner, the said edges will ream out the soil below the end of the casing as indicated in Fig. 3 to permit the said casing to move downwardly in the usual manner.

When it is desired to remove the tool from 125 the well, it is drawn upward until the upper ends of the dogs 15 engage the lower end of the well casing. The lower ends of the dogs are now in engagement with the upper end of the main portion 35 of the support, and 130

when the tool is drawn upward a short distance farther, the dogs will be pushed downward, drawing down the support 35 and compressing the spring 44. It will be noted that the upper outer corner of each dog 15 is slightly beveled as shown at 47, and as soon as the dogs have reached the lower ends of the slots 2, the farther upward movement of the tool will push in the upper ends of the dogs, moving the key heads 13 into contact. The reduced portion 41 of the wedge support is at this time in such position that the lower ends of the keys may move inwardly and as the dogs 15 move entirely into the well casing, the keys again take the position of Fig. 1, thus locking the wedges in lowered position.

The wedges remain in the lowered position after the tool is withdrawn at the top of the casing. When it is desired to reenter the reamer in the casing, a small rod is inserted in the lower exposed portions of the wedges, and a small wedge or lever is placed between the said rod and the bottom of the casing 1, to release the tension of the spring 44. The dogs 15 are thus released, and they are moved to the top of the slots 2, and pushed into the casing, as shown in Fig. 1. A ring or like element is placed over the casing 1, at the dogs 15, to hold them in place in their inward position. The tool is now entered at the upper end of the well casing, and is permitted to move into the casing, until the lower ends of the dogs 15 are engaged by the casing. The casing now holds the dogs in inward position, and the ring may be withdrawn. As soon as the dogs pass below the lower end of the well casing, they move outward, and the wedge support 35 is released, and the wedges move upward, forcing the bits into the working position. When the tool is raised to bring the dogs 15 into contact with the lower end of the casing, the dogs are forced downward to the lower ends of the slots 2, and then inward into the casing, so that they may move upward through the well casing. It will be noticed that the wedges have openings 34 for engagement by a tool in order that they may be pulled downward into the position of Fig. 1.

When the dogs 15 are drawn downwardly in the slots 2, by their engagement with the lower end of the well casing, the wedges and the wedge support are moved downward with the dogs. The keys, however, by reason of the engagement of their rounded heads with the rounded openings of the dog support 9, cannot move downward, being held by the dog support 9 in the position shown in Figs. 1 and 3 of the drawings. As soon as the shoulders 43 pass below the lower ends of the keys, the dogs move inward. There is sufficient room for the dogs between the cam extension 42 of the wedge supports

and the periphery of the tubular casing 1, and the inward movement of the dogs forces also the keys inward.

The notches 17 on the depending arms 12 of the dog support receive the cross heads 16 of the dogs to permit the said dogs to move far enough inwardly to bring their outer edges flush with the periphery of the tubular support when in this position, and they are so held by their engagement with the well casing, the said dogs cannot move downwardly for the dog support is fixed with respect to the tubular casing. The dogs cannot move downward until they move outward.

Openings normally closed by plugs 48 are provided in the tubular casing 1 at a point such that the pin 38 may be brought into register with the said openings to permit the removal of the pin to detach the wedges from the wedge support, to permit the removal of the wedges. When the wedges have been removed by simply withdrawing them from the lower end of the tubular casing 1, the bits may then be detached from their support. They are normally held in connection with the support by the wedges and the bit support and the bits are connected to the wedge support by the wedges.

It will be evident from an inspection of Fig. 3 that the bit support could not move downward with respect to the wedges because the bits cannot be any further extended at their upper ends and the wedges are of too great thickness to pass between the upper ends of the bits and the bit support. No other connection is necessary between the bit support and the wedge support.

I claim:—

1. The combination with an under-reamer comprising a tubular casing provided at its upper end with oppositely arranged longitudinally extending slots, and at its lower end with bits mounted to swing beyond the periphery of the casing into working position, wedges movable longitudinally of the casing for extending the bits, a wedge support to which the wedges are connected, and a spring acting normally to move the wedge support in a direction to cause the wedges to extend the bits, of means for holding the wedges in inoperative position against the resistance of the spring, said means comprising dogs slidable in the slots longitudinally of the casing and movable radially with respect thereto, the wedge support having a cam extension between the dogs for moving them radially outward to extend them beyond the periphery of the casing when the wedges are moved to operative position, and into position to engage the lower end of the well casing, said dogs being adapted for engagement with the inner surface of the well casing to hold them in inward position to prevent the upward movement of the

wedge support to extend the bits, a dog support rigid with the casing and having a bore for receiving the cam extension and having radial openings from the bore at the dogs, 5 keys in the openings of the dog support, the lower ends of the keys being beveled for engagement by the cam extension and said keys engaging the dogs, the dogs having cross heads extending across the openings 10 for the keys of the dog support to limit the inward movement of the dogs.

2. The combination with an under-reamer comprising a tubular casing provided at its upper end with oppositely arranged longitudinally extending slots, and at its lower end with bits mounted to swing beyond the periphery of the casing into working position, wedges movable longitudinally of the casing for extending the bits, a wedge support to which the wedges are connected, 15 and a spring acting normally to move the wedge support in a direction to cause the wedges to extend the bits, of means for holding the wedge support from upward movement, said means comprising dogs in the slots movable longitudinally and radially of the casing, the wedge support having a cam extension moving between the dogs to move them outward beyond the periphery of the casing, the dogs preventing upward movement of the said support when in position within the periphery of the tubular casing, a dog support rigid with the casing at the slot and having a bore for receiving the cam extension and having radial 30 openings at the dogs, keys within the openings movable radially of the dog support and having means for engaging the support to prevent longitudinal movement thereof, 35 the dogs having cross heads extending across the openings for the keys, and the extension engaging the keys to move the dogs outward, the wedge support having shoulders for engagement by the lower ends of the 40 dogs when the dogs are moved downwardly in the slots to cause the said wedge support to move with the dogs, and the slots being of sufficient length to permit the lower ends of the dogs to move below the dog support 45 to permit them to move inwardly when at the lower ends of the slots.

3. The combination with an under-reamer comprising a tubular casing provided at its upper end with oppositely arranged longi-

tudinally extending slots, and at its lower end with bits mounted to swing beyond the periphery of the casing into working position, wedges movable longitudinally of the casing for extending the bits, a wedge support to which the wedges are connected, and a spring acting normally to move the wedge support in a direction to cause the wedges to extend the bits, of means for holding the wedge support against the resistance of the spring, said means comprising dogs mounted for longitudinal sliding movement of the slots and for radial movement with respect to the tubular casing, the wedge support having a cam extension moving between the dogs and extending them beyond the periphery of the tubular casing when the wedge support moves upward to cause the wedges to extend the bits, a dog support rigid with the casing at the slots, and having means for engagement by the dogs 75 when within the periphery of the tubular casing to lock the dogs at either end of the slots with the spring of the wedge support under compression.

4. The combination with an under-reamer comprising a tubular casing provided at its upper end with oppositely arranged longitudinally extending slots, and at its lower end with bits mounted to swing beyond the periphery of the casing into working position, means movable longitudinally of the casing for extending the bits, and a spring normally acting to move the said means in a direction to extend the bits, of means for holding the said expanding means against the resistance of the spring, said holding means comprising dogs mounted for longitudinal sliding movement in the slots and for radial movement with respect to the casing, a cam connected with the expanding means and moving between the dogs to extend them beyond the periphery of the casing when the expanding means moves upward to expand the bits, a dog support rigid with the casing at the slots and having means for engagement by the dogs when within the periphery of the tubular casing, to lock the dogs at either end of the slots with the spring under compression.
